UNITED STATES PATENT OFFICE.

WILLIAM B. WARREN, OF PEORIA, ILLINOIS.

DRAFT APPLIANCE FOR LOCOMOTIVE-BOILERS.

SPECIFICATION forming part of Letters Patent No. 625,225, dated May 16, 1899.

Application filed December 14, 1898. Serial No. 699,246. (No model.)

To all whom it may concern:

Be it known that I, WILLIAM B. WARREN, a citizen of the United States, residing at Peoria, in the county of Peoria and State of Illinois, have invented certain new and useful Improvements in Draft Appliances for Locomotive-Boilers, of which the following is a full, clear, and exact description, reference being had to the accompanying drawings, forming part of this specification.

My invention relates to a draft appliance for the boilers of locomotives in which I provide for the use of the exhaust-steam from the engine-cylinders in conjunction with a fresh-air inlet, whereby the steam and air are mixed in a chamber common to both to be directed from an outlet beneath the smoke-arch of the boiler across the latter to the smoke-stack.

My invention consists in features of novelty hereinafter fully described, and pointed out in the claims.

Figure I is a vertical longitudinal sectional view taken on the line I I, Fig. II, through the head end of a locomotive-boiler and my appliance. Fig. II is a view in front elevation of a boiler and my appliance shown applied thereto, the head end of the boiler being removed. Fig. III is a vertical sectional view taken on the line III III, Fig. I. Fig. IV is an enlarged detail view of the air-inlet-valve yoke.

1 designates a boiler having a smoke-arch 1^a, and 2 a smoke-stack. 3 are the live-steam pipes that lead from the steam-space in said boiler to the engine-cylinders. (Not shown.)

4 designates a steam-pipe located in line with the smoke-stack and having within its interior two passage-ways 5, separated by a partition 6. These passage-ways 5 are in communication with the engine-cylinders by pipes, (not shown,) through which the exhaust-steam from said cylinders may be conveyed to said passage-ways to be discharged into a single steam-chamber 7, located above the passage-ways 5 and common to both passage-ways. At the upper end of the steam-chamber 7 is a nozzle 8.

9 designates a housing mounted upon the pipe 4 beneath the smoke-arch, so that its outlet does not intrude within the latter to obstruct the smoke-arch, and containing a

mixing-chamber 10. The mixing-chamber 10 surrounds the upper end of the pipe 4 and extends above the upper end of said pipe to 55 a nozzle 11, that forms an outlet from said chamber.

12 designates a fresh-air-outlet pipe that has communication through the housing 9 to the mixing-chamber 10. This pipe 12 extends 60 to the wall of the boiler, where it is connected to a valve-box 13, that provides communication from the pipe 12 to the exterior of the boiler. 14 designates a valve seated against the outer end of said valve-box 13 and adapted 65 to swing in sliding contact with the end of said box. This valve is supported by a yoke 15, one end of which is swiveled in an ear 13^a on the valve-box 13. This yoke is shown in detail in Fig. IV. In the center of the yoke 70 15 is an upright pin 16, on which the valve 14 is seated, said valve being held to its seat against the end of the valve-box 13 by a spring 17, that surrounds the pin 16. The yoke is formed with a free end 15^a, that receives the 75 attachment of a link 18. The valve 14 is adapted to be manipulated by the engineer in the cab, and to provide for such manipulation I employ an operating-rod leading from the cab and connected to a crank-arm 19, (see 80 Fig. II,) mounted on a rock-shaft 20. The rock-shaft 20 is supported in brackets 21 and extends downwardly, so that its lower end is approximately in line with the link 18, connected to the free end of the yoke 15. The 85 lower end of the rock-shaft is provided with a crank-arm 22, that receives the connection of the opposite end of said link 18 from its end that is connected to the valve-holding yoke. It will thus be observed that the valve 90 may be readily controlled by the engineer while in his cab by operating the rod leading thereto to turn the crank-arm 19, and thereby rock the shaft 20 to throw the link 18 in either direction for the purpose of allowing the ingress of more or less fresh air past the valve 95 14 into the fresh-air pipe 12 and thence into the mixing-chamber 10.

The exhaust-steam from the engine-cylinders flows through the passage-ways 5 into 100 the chamber 7, passing into the mixing-chamber 10, and thereby creates a suction in said mixing-chamber, drawing fresh air through the pipe 12 into said mixing-chamber to be

combined with the steam, from which the combined steam and air are carried under the pressure of the steam through the nozzle 11 and directed upwardly from beneath the smoke-arch across the latter into the smoke-stack to create the desired draft and creating a draft of much greater intensity than can be accomplished by the use of exhaust-steam alone.

10. By the use of my appliance I am enabled to use larger exhaust-pipe nozzles than is possible where exhaust-steam alone is employed, and I thereby reduce the back pressure in the engine-cylinders over what is present in the 15 use of exhaust-steam alone when creating the same draft.

Having thus described my invention, the following is what I claim as new therein and desire to secure by Letters Patent:

20. 1. In a draft appliance, the combination, with a boiler having a smoke-arch, and a smoke-stack, of an exhaust-steam pipe, a housing having its outlet located beneath the smoke-arch in line with the smoke-stack and 25 containing a mixing-chamber into which said steam-pipe is adapted to empty and a fresh-air-inlet pipe having communication with said mixing-chamber; substantially as described.

2. In a draft appliance, the combination, 30 with a boiler, having a smoke-arch, and a smoke-stack; of an exhaust-steam pipe, a housing having its outlet located beneath the smoke-arch and containing a mixing-chamber into which said steam-pipe is adapted to 35 empty, a fresh-air-inlet pipe having communication with said mixing-chamber, and a valve arranged to control the entrance of air to said pipe; substantially as described.

3. In a draft appliance for locomotive-boilers, the combination, with a boiler, having a smoke-arch, and a smoke-stack; of an exhaust-steam pipe having communication with

the engine-cylinders and containing a steam-chamber, a housing having its outlet located beneath the smoke-arch and containing a 45 mixing-chamber into which said steam-chamber is adapted to empty, a fresh-air-pipe having communication with said mixing-chamber, and leading to the exterior of said boiler, a valve closing the entrance to said air-pipe, 50 and means for operating said valve; substantially as described.

4. In a draft appliance for locomotive-boilers, the combination, with a boiler, having a smoke-arch, and a smoke-stack; of an exhaust-steam pipe having communication with the engine-cylinders, a nozzle at the end of 55 said exhaust-pipe a mixing-chamber into which said exhaust-pipe is adapted to empty, a nozzle located beneath the smoke-arch at 60 the outlet of said mixing-chamber, a fresh-air pipe having communication with said mixing-chamber, a valve arranged to control the entrance of air into said air-pipe; substantially as described.

5. In a draft appliance for locomotive-boilers, the combination of an exhaust-steam pipe having communication with the engine-cylinders, a mixing-chamber into which said exhaust-steam pipe is adapted to empty, said 70 mixing-chamber being provided with an outlet-nozzle, a fresh-air pipe having communication with said mixing-chamber, and leading to the exterior of the boiler, a valve adapted to control the entrance of air into 75 said air-pipe, a yoke supporting said valve, and a rock-shaft having connection with said yoke through means of which said valve may be operated; substantially as described.

WILLIAM B. WARREN.
